KALMAN VON KANDO, OF VADO LIGURE, ITALY, ASSIGNOR, BY MESNE ASSIGNMENTS, TO, WESTINGHOUSE ELECTRIC & MANUFACTURING COMPANY, OF EAST PITTSBURGH, PENNSYLVANIA, A CORPORATION OF PENNSYLVANIA.

SUSPENSION OF LIQUID-CONTAINERS ON RAILWAY-VEHICLES.

1,343,241.

Specification of Letters Patent. Patented June 15, 1920.

Application filed December 9, 1914. Serial No. 876,379.

To all whom it may concern:

Be it known that I, KALMAN VON KANDO, a subject of the Emperor of Austria and of the King of Hungary, and a resident of 5 Vado Ligure, in the Kingdom of Italy, have invented a new and useful Improvement in the Suspension of Liquid-Containers on Railway-Vehicles, of which the following is a specification.

10 This invention relates to an improvement in the suspension of containers for liquid on railway vehicles, and has for its object to provide an improved construction by which the strains experienced by the vehicle during its movement will not be communicated to the walls of the container.

When a large and heavy container for liquids is mounted directly upon the frame of the vehicle the walls require to be massive and strongly braced since the vehicle frame is elastic and is subject to deformation due to running strains when the vehicle is in service, and such strains are communicated to the container walls and give 25 rise to heavy and dangerous stresses. The forces thus produced may be in some instances so great that it is practically impossible to make the container sufficiently strong, within the limits of weight allowed, 30 to withstand them.

It is the object of the present invention to provide an improved construction whereby a container can be suspended from the frame in such a manner that deformation of the vehicle frame can occur without the container being similarly affected.

According to my invention I provide a frame in which the container is supported, this frame being suspended from the vehicle frame in such a manner that alterations in the form of the latter due to running strains can occur without deforming the container walls.

In order that the invention may be clearly understood it will now be described with reference to the accompanying drawings in which Figure 1 is a side elevation partly sectional showing the under part of a railway vehicle from the frame of which a liquid container is supported in accordance with my invention. Fig. 2 is an under-plan view of the same. Fig. 3 is a section on the line III-III of Fig. 2. Fig. 4 is a side elevation partly sectional and Fig.

5 is a plan view partly sectional showing a 55 detail. Fig. 6 is an end elevation partly sectional of the part shown in Fig. 4 and Fig. 7 is a section on the line VII-VII of Fig. 4.

Referring now to the drawings, a container indicated in broken and hatched outline at 1 is supported in a frame consisting of two pairs of parallel members 2, 3 and 4, 5 respectively. The members 2 and 3 are supported by stirrups 6 from the members 4, 5, said stirrups consisting of straps bent to a rectangular form, the upper parts of which surround the members 4, 5, the lower parts being provided with orifices 7 through which the members 2, 3 are passed. 70 This construction will be clearly understood from Figs. 3 and 6 of the drawings. The frame members 4, 5 are provided with seats 8 which rest upon knife edges 9 which are firmly secured between plates 10 of substantially triangular form (see Fig. 4) said plates being provided with knife edges 11 which in their turn are borne upon seats 12 secured in plates 13 which are riveted to stays or links 14, 15, 16, these latter being 75 directly supported from the side beams 17 of the car. The plates 10 on each side of the car are further connected by links 18 pivoted thereto as shown. It will be readily seen that the plates 10 in effect form 80 bell crank levers which are pivoted at 11, 12 to the frame work of the vehicle and directly support the frame 2, 3, 4 and 5, through the knife edges 9. The stirrups 6 are connected through links 19 to bell-crank 85 levers 20, pivoted at 21 on the cross bearers 22 which form part of the framework of the vehicle, the other end of said bell crank levers 20 being connected by a link 23.

It will be readily seen from the construction hereinabove described that the weight of the container is, in the first instance, borne by the lower members 2, 3 of the frame and is transferred through the stirrups 6 to the cross members 4, 5 and from thence through the knife edges 9 and 12 to the stays 14, 15, 16 carried by the frame of the vehicle. Movement of the container longitudinally of the vehicle is prevented by the members 4, 5 of the frame and movement in a lateral direction is prevented by the side beams 17 of the vehicle.

Any downward movement of the frame

member 4 at one end of the container will, through the plates 10 and connecting link 18, be transmitted to the corresponding plates 10 at the other end of the container 5 and cause an upward movement of the frame member 5. Consequently the center of gravity of the container, which may be considered to lie in a plane midway between its ends, will neither be raised or lowered.

10 Owing to the flexible nature of the connection between the frame 2, 3, 4, 5, and the vehicle frame 17 any deformations of the latter will not result in strains being transmitted to the side of the receptacle.

15 Furthermore, if one side of the receptacle is tilted owing to an upward movement of the frame member 3, for example, this movement is transmitted through the stirrup 6, link 19, bell crank 20, link 23, and 20 corresponding bell crank 20 and stirrup 6 at the other side of the vehicle, to the frame member 2 and causes the same to descend. Consequently in this case also the center of gravity which may be considered to be in a 25 longitudinal plane approximately midway between the sides of the tank is also neither raised nor lowered. The construction therefore substantially prevents movement of the center of gravity of the tank when the vehicle is tilted either sidewise or in a longitudinal direction.

30 The construction can be further improved by providing additional links 24 connected at one end to the stirrups 6 and at their other ends to bell cranks 25 pivoted at 26 to the vehicle frame, the free ends of said bell cranks being connected by a link 27.

35 It will be readily understood without further explanation that a lateral movement 40 of one end of the container and frame in a horizontal plane will thereby cause a corresponding movement of the other end of the container in an opposite direction and will in effect rotate the same around a vertical axis passing through its center of 45 gravity. Consequently lateral movements due to centrifugal forces and other stresses under ordinary service conditions will be avoided.

50 I claim as my invention:

55 1. In a vehicle, the combination with a body portion, of a frame, levers pivotally connected to the frame, and means for pivotally supporting the body portion on said levers to permit the same to effect a movement of rotation relative to the frame while maintaining the center of gravity thereof substantially stationary.

2. In a vehicle, the combination with a

3. The combination with a vehicle, of a frame adapted to support a receptacle for liquid, bell crank levers pivoted to the vehicle frame and pivotally supporting said receptacle frame, and links connecting said 70 bell crank levers in pairs.

4. The combination with a vehicle, of a quadrangular frame, bell crank levers at the corners thereof pivotally supporting the same, horizontal pivots connecting said 75 bell crank levers and the vehicle frame, and links connecting said bell crank levers in pairs.

5. The combination with a vehicle, of a frame adapted to support a receptacle for 80 liquid, bell crank levers supported on horizontal pivots substantially perpendicular to the longitudinal axis of the vehicle and pivotally supporting said receptacle frame, and links connecting said bell crank levers 85 in pairs.

6. The combination with a vehicle, of a frame adapted to support a receptacle for liquid, bell crank levers pivotally connected to said frame and pivoted to the vehicle 90 frame by horizontal pivots parallel with the longitudinal axis of the vehicle, and transverse links connecting said bell crank levers in pairs.

7. The combination with a vehicle, of a 95 frame adapted to support a receptacle for liquid, bell crank levers connected together and pivoted by vertical pivots to the vehicle frame, and links connecting said bell crank levers to the receptacle frame. 100

8. The combination with a vehicle, of a plurality of bell crank levers pivoted to the vehicle frame by horizontal pivots perpendicular to the longitudinal axis of the vehicle, links connecting said bell crank levers 105 in pairs, a pair of bell crank levers pivoted to the vehicle frame by horizontal pivots parallel with the longitudinal axis of the vehicle, links connecting said bell crank levers, and a frame pivotally supported on 110 the bell crank levers and adapted to support a receptacle for liquid.

9. The combination with a vehicle, of a plurality of bell crank levers pivoted to the vehicle frame by horizontal pivots, links 115 connecting said bell crank levers in pairs, a frame adapted to support a receptacle for liquid pivotally connected to said bell crank levers, a pair of bell crank levers connected together and pivoted by vertical pivots to the vehicle frame, and links connecting said bell crank levers to the receptacle frame. 120

10. In a vehicle, the combination with a

frame, of a body portion, and means for pivotally supporting said body portion on the frame to permit the former to effect a movement of rotation relative to the latter either about its vertical or horizontal axis and maintain the center of gravity of the body portion substantially stationary.

12. In a railway vehicle, the combination with the vehicle frame, of a container-supporting frame, and means for suspending said container-supporting frame from the vehicle frame and for limiting the movements of the container laterally and longitudinally of the vehicle.

13. In a railway vehicle, the combination with a plurality of wheels, a frame, and a

container, the lowest point on either the frame or the container being located above the lowest point on the periphery of the wheels, of means for suspending the container from said frame to prevent the transmission of any running strains through the container or material changes in the position of the center of gravity of the container.

In testimony whereof I have hereunto subscribed my name this 28th day of October, 1914.

KALMAN VON KANDO.
